UNITED STATES PATENT OFFICE.

ROBERT B. McMASTERS, OF PLYMOUTH, NEW YORK.

MITTEN.

SPECIFICATION forming part of Letters Patent No. 709,350, dated September 16, 1902.

Application filed March 27, 1902. Serial No. 100,287. (No model.)

To all whom it may concern:

Be it known that I, ROBERT B. McMASTERS, a citizen of the United States, residing at Plymouth, in the county of Chenango and State 5 of New York, have invented certain new and useful Improvements in Gloves and Mittens; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 This invention relates to new and useful improvements in mittens and gloves in which double protecting-strips are provided to cover the seams joining the different parts of the mitten or glove together, thereby rendering 20 the same more efficient and durable.

In making the seams which join the different parts of a glove or mitten together three objects should be kept in view: first, the covering of the original joining-seam in such 25 a way that it will be protected from wear and the action of the elements; second, to provide for relieving the joining-seam of a percentage of lateral strain which comes upon it in actual service; third, durability and 30 wearing life of the protecting shield or strip. The improvement which I have made provides for the covering of the first strip which shields the joining-seam by a second shield or strip of cloth or skin, said second shield 35 or strip being either formed a part of the first shield or strip which covers the joining-seam or separate therefrom and made of one or more thicknesses of cloth or skin.

My invention will be hereinafter more fully 40 described in detail and then specifically defined in the appended claims, and is clearly illustrated in the accompanying drawings, which, with the letters of reference marked thereon, form a part of this application, and 45 in which drawings—

Figure 1 is an elevation of the front or palm part of the mitten embodying my improvements, and Fig. 2 is an edge view of the same. Fig. 3 is a sectional view of the 50 back and palm sides of a mitten, respectively, showing welt and joining-seams, the protect-

ing-strip folded twice upon itself and in section. Fig. 4 is a sectional view showing in section parts with the welt continued to form the two protecting-pieces. Fig. 5 is a similar 55 view showing the welt used to form one of the protecting-strips bent upon itself and over which is stitched a second guard or protecting-strip. Fig. 6 is a similar view in section, showing a slight modification in which 60 the welt is bent upon itself, with its ends forming two protecting-strips stitched one over the other; and Figs. 7 and 8 are different modifications, each of which, however, shows the essential feature of my invention 65 which comprises the double protecting-shield.

Reference now being had to the details of the drawings by letter, A and B designate, respectively, the back and palm sides of a mitten, and C designates a welt, which is 70 stitched between the inner ends of the pieces A and B, as shown, by stitching represented by letter E, which is the usual construction in the manufacture of mittens.

D designates a protecting-strip, which in 75 the form illustrated in Fig. 3 of the drawings comprises a single piece of cloth or skin, which may be of one or more thicknesses and which is stitched to the pieces A and B by two rows of stitching designated by letters F and F' at locations adjacent to the stitching of the welt. The said protecting-strip D is bent upon itself at two locations, (designated by letters G and G',) and by means of the row 80 of stitching H the portion of the protecting-strip is stitched to part B adjacent to the location where said piece is bent upon itself, and the free end of the piece which is bent upon itself and stitched as described is 85 stitched to the piece A by means of the stitching H', said stitching H' passing through two thicknesses of the protecting-strip, and the outer overlapping end of the protecting-strip D is stitched at K through the two thicknesses of strip D, bent upon themselves, and the extreme outer end of strip D is sewed through 90 the piece B, as clearly shown in the drawings, thereby producing a double protecting-guard for the joining-seam.

In Fig. 4 I have shown the welt C as being 95 integral with the protecting-strip and stitched at N to the piece B, after which said protect-

ing-strip is bent upon itself and stitched at N' and N², securely holding the said strip to the parts B and A, respectively, after which the outer flap is stitched in a similar manner, 5 as shown in Fig. 3.

In Fig. 5 I have shown a construction somewhat similar to the others, excepting that the welt forms one layer of the protecting-strip, while a separate protecting-strip D' is provided which is sewed over the inner protecting-strip.

In Fig. 6 the welt is formed by being bent upon itself, with its two ends outwardly disposed and bent upon themselves and stitched 15 in the manner illustrated in the other figures, and in Figs. 7 and 8 are slight modifications, each of which, however, shows the essential feature of my invention, for which I claim advantages over the other forms of construction 20 heretofore patented, in that I provide double protecting-strips or guard-pieces for covering the seams.

From the foregoing it will be observed that a double guard-strip is provided which protects perfectly, for the reason that it covers the joining-seam beneath three folds of flexible skin or cloth and will withstand more lateral strain than a single guard-piece, for the reason that each fold has a stitched point of 30 bearing on the back or front of the mitten or glove on either side of the closing-seam, thereby making the life of the mitten or glove longer and producing practically two inseamed guards with an outseamed guard thrown over them.

I am aware that it is common in the art to make gloves and mittens with protecting-strips which cover the seams which join dif-

ferent parts of the mitten or glove together, and hence I do not claim, broadly, said construction. 40

Having thus fully described my invention, what I claim as new, and desire to secure by Letters Patent, is—

1. As an improved article of manufacture, 45 a glove or mitten with double protecting-guards, each sewed to the back and palm side thereof respectively by separate rows of stitching, as set forth.

2. As an improved article of manufacture, 50 a glove or mitten, comprising in combination with the back and palm sides thereof with a welt in the joining-seam thereof, a protecting-shield folded twice upon itself forming an inner shield covering the joining-seam, and an 55 outer shield stitched over the inner shield, as set forth.

3. As an improved article of manufacture, 60 a mitten or glove comprising front and back sides joined together by a seam with welt there- in, a double protecting guard-piece of cloth or skin which is stitched to said front and back pieces adjacent to the welt, one end of the protecting or guard piece bent upon itself and stitched to said front and back respectively, 65 the outer end of the protecting-strip being bent upon itself and stitched over the inner end, thus forming a double guard-piece, as set forth.

In testimony whereof I affix my signature 70 in presence of two witnesses.

ROBERT B. McMASTERS.
